CLAIM

The ornamental design for a combined lid and container as shown and described.

DESCRIPTION

FIG. 1 is a top perspective view of a combined lid and container showing my new design;

FIG. 2 is a first side view thereof;

FIG. 3 is a second side view thereof;

FIG. 4 is a third side view thereof;

FIG. 5 is a fourth side view thereof;

FIG. 6 is a top plan view thereof;

FIG. 7 is a bottom plan view thereof; and,

FIG. 8 is an exploded top perspective view thereof.

Broken lines show portions of the combined lid and container that form no part of the claimed design.

1 Claim, 5 Drawing Sheets
